GAS ENGINE VALVE

Application filed October 2, 1929. Serial No. 396,664.

This invention relates to internal combustion engines and has particular reference to the cylinder or slide valve type of internal combustion engine and a system of lubrication therefor.

The principal object of this invention is to provide an internal combustion engine having a slide valve for controlling the intake of the combustible mixture into the engine cylinder, and a second slide valve for controlling the exhaust of the burned gases from the engine cylinder, both intake and exhaust valves being driven by the engine crank shaft.

Another object of this invention is to provide means for lubricating the valve mechanism described, which comprises over-supplying the valves with lubricant, the latter being supplied continuously in greater quantity than is necessary, whereby efficient and sufficient lubrication is obtained at all times.

These and other objects of this invention are obtained in a preferred embodiment thereof, which comprises intake and exhaust valves of the trunk or cylinder type placed on opposite sides of the cylinder which they serve and being driven directly by means of spur gears from the crank-shaft of the engine. The valves are supplied with oil from their own reservoir, so that the lubricating oil is always good, being uncontaminated by grit, carbon flakes, etc., which is found in the crank case oil.

For a better understanding of the invention, reference is made to the accompanying drawings, in which

Figure 1 is a vertical section, partly schematic, of a piston valve engine embodying my invention as seen along the line 1—1 of Fig. 2, during the intake stroke;

Fig. 2 is a vertical section through the intake piston valve as seen along the line 3—3 of Fig. 1;

Fig. 3 is a plan view of the new engine; and

Fig. 4 is an enlarged fragmentary view of one of the piston valves showing the oil seal ring.

In the drawing, numeral 10 designates the engine block having a series of cylinders

11, corresponding pistons 12, and a common crank shaft 13 to which each piston 12 is connected by the connecting rod 14. Each cylinder is fitted with the usual spark plug 15, the intake port 16 and the exhaust port 17.

Adjacent opposite sides of the engine cylinder 12 are the valve cylinders 18 and 19, the former containing the intake valve 20 and the latter the exhaust valve 21. These valves are cylindrical pistons and are driven from the engine crank shaft 13, the intake valve 20 being connected by connecting rod 22 to an individual crank-shaft 23 rotating in oil reservoir 24 and having its connected spur gear 25 driven by the spur gear 26 of engine crank shaft 13. The engine crank-shaft gear 26 also drives the gear 28 of crank-shaft 29, which is connected to exhaust piston 21 by connecting rod 30 and rotates in oil reservoir 31. Cover plates 33 permit access to the valve crank-shafts 23 and 28.

The intake valve 20 is generally of the trunk type, but has an oblong diametral port 32 which is adapted to register on one side with the intake port 16 of the engine cylinder 11, and at its opposite side with the intake passage 33 through the water cooling jacket 34, and connected to the carburetor by connections not shown. Between the head 35 and the ceiling 36 of the piston 20 is an oil reservoir 37 which discharges through passages 38 around port 32 into the bell and from there into the reservoir 24 below. The head 35 and skirt 39 of the piston 20 are equipped with the oil rings 40 and 40', respectively, which are shown in greater detail in enlarged Fig. 4. These oil rings 40 are chamfered at their upper inner surfaces to form an oil collecting groove 41, which communicates through a plurality of oil holes 42 with the oil reservoir 37 into which the surplus oil collected thereby flows. The similar oil ring 40' in the valve skirt 39 discharges through oil holes 42' into the bell of the valve and reservoir 24.

Immediately below the port 32 are mounted two compression rings 43 which serve to seal the intake port 16 in the wall of engine cylinder 11 during the firing and compres-

sion strokes of the engine piston 12, thus preventing all leakage of gas into the valve chambers. Inasmuch as the exhaust valve 21 is constructed in exactly the same way as the intake valve 20 just described, it will not be necessary to describe the same, the port 32' thereof registering with the exhaust port of engine cylinder 11, and with the exhaust passage 44 through the water jacket 34' during the scavenging stroke of the engine piston 12.

Continuously drawing oil from valve oil reservoirs 24 and 31 are the oil pumps 45 and 45', respectively, which are driven in the usual way by means not shown, such as by a connection with the crank-shaft 13 of the engine or the like. These oil pumps 45 and 45' through pipes 46 and 46' inject oil under pressure into tanks 47 and 47' located immediately above intake valve 20 and exhaust valve 21, respectively. It will be seen that the cylinders 18 and 19 in which respective valves 20 and 21 move, are headless and serve as breathers to relieve the pressure and suction created by the movement of these piston valves.

The tanks 47 and 47' are closed by cover plates 48 and 48', respectively, which are readily removable for access to the valve chambers. Mounted upon the under sides of respective cover plates 48 and 48' are screens 49 and 49', against which the oil injected by pipes 46 impinges. A portion of this oil passes through these screens and falls into sumps 50 and 50', from which it flows through respective down pipes 51 and 51' into oil reservoirs 24 and 31 respectively, cooling the head of engine cylinder 11 and the walls of valve cylinders 18 and 19.

The remainder of the oil, which was caught by screens 49 and 49', drips downwardly therefrom upon the heads of valve pistons 20 and 21, being retained thereon because of the surrounding walls of the valve cylinders during the downward and upward strokes of the corresponding valves until at the highest point of their upward stroke the heads of the pistons lie flush with the upper rim of their cylinders, whereupon the oil remaining thereon flows off into sumps 50 and 50'. However, the majority of this oil creeps along the cylinder wall to be collected by oil rings 40, from which the oil passes through oil holes 42 into oil reservoir 37, oil passages 38 and through the bell of the valve into the oil reservoir 24. Some of this oil is trapped in well 37 because the openings to oil passages 38 are placed above the bottom thereof, and this trapped oil cools the port of the valve, this being especially effective in exhaust valve 21. The oil flowing through the oil holes 38 cools the port at its sides. Similarly, the oil collected by oil ring 40' in the skirt of the valve, flows through oil holes 42' into reservoir 24. In this way an over-supply of oil is provided whereby a thorough

lubrication of the cylinder valves is provided. The lower ends of the valve cylinders 18 and 19 and valves 20 and 21 are lubricated by the splash of their respective crank shafts 23 and 29.

The operation of the valve mechanism and the lubricating means therefor will be apparent from the foregoing description thereof. It will be seen that the new valve mechanism has many important advantages. Among these advantages are the decreased number of parts as compared to present valve mechanisms, long life because of effective lubrication and freedom from excessive heat, the only part of the valves which is subjected to the flame during the firing stroke being the rings 43. The valves are light and inexpensive to manufacture and require no adjustment nor are there any parts which are liable to breakage, deterioration, or excessive wear, such as springs, rockers, poppets, or the like. Furthermore, the intake and exhaust paths of the gases are direct and unobstructed by valve heads, stems or the like, thus allowing shorter intake and exhaust periods and assuring complete charging and scavenging.

While a preferred embodiment of this invention has been illustrated and described herein, it is to be understood that the invention is not limited thereby, but is susceptible of many variations in form and detail within its scope. For example, while each engine cylinder has been illustrated as equipped with separate intake and exhaust valves, a single piston valve of the type described having intake and exhaust ports or employing a single port for both intake and exhaust, will be found practical upon smaller bore engines.

I claim:

1. In an internal combustion engine having a gas port in the wall of the explosion chamber thereof, the combination of a slide valve having a port adapted to register with said cylinder port, passages in said valve surrounding the said port thereof for cooling the same, and a pump for continuously supplying a cooling fluid to said passages.

2. In an internal combustion engine having a gas port in the wall of the explosion chamber thereof, the combination of a slide valve having a port adapted to register with said cylinder port, oil tanks at the opposite ends of travel of said valve, and means driven by said engine for applying oil from said tanks to the corresponding ends of said valve.

3. In an internal combustion engine having a gas port in the wall of the explosion chamber thereof, the combination of a slide valve having a port adapted to register with said cylinder port, said valve having longitudinal oil passages around said valve port, an oil tank, and means driven by the engine for continuously transferring oil from said tank

to the head of said valve for flow through the passages thereof.

4. In an internal combustion engine having a gas port in the wall of the explosion chamber thereof, the combination of a hollow slide valve having a port adapted to register with said cylinder port, said valve being arranged for vertical movement and having perforated walls for collecting oil, an oil reservoir at the lower end of travel of said valve, and means driven by the engine for transferring oil from said reservoir to the head end of said valve.

5. In an internal combustion engine having a gas port in the wall of the explosion chamber thereof, the combination of a slide valve having a port adapted to register with said cylinder port, said valve being arranged for vertical movement, means supplying oil to the sliding surfaces of said valve, oil collecting grooves in the sliding surfaces of said valve, and passages from said grooves through the interior of said valve for discharging the surplus oil collected by said grooves.

6. In an internal combustion engine having a gas port in the wall of the explosion chamber thereof, the combination of a slide valve having a port adapted to register with said cylinder port, said valve being arranged for vertical movement, means at the top end of travel of said valve for deflecting oil upon the head thereof, and means driven by said engine for forcing oil against said means.

35 7. In an internal combustion engine having a gas port in the wall of the explosion chamber thereof, the combination of a slide valve having a port adapted to register with said cylinder port, said valve being arranged for vertical movement, a vertical screen mounted adjacent the top end of travel of said valve, and means for directing oil against said screen, whereby a portion thereof passes through said screen and a portion is collected thereby to drip upon the head of said valve.

8. In an internal combustion engine having a gas port in the wall of the explosion chamber thereof, a slide valve having a port adapted to register therewith, an oil tank having a communication with said valve means for introducing oil into said tank, and a deflector in said tank for deflecting a portion of the oil introduced into the tank by said means through said communication to said valve.

9. In an internal combustion engine having an explosion cylinder, a vertical valve cylinder adjacent said explosion cylinder, a piston valve in said valve cylinder for controlling communication to and from said explosion cylinder and driven by the engine, means for oiling the walls of said valve cylinder, an oil reservoir in the valve, oil collecting rings on the sliding surfaces of said valve, and connections between said collecting rings

and said reservoir, whereby the oil collected by said rings is discharged into said reservoir.

10. In an internal combustion engine having an explosion cylinder, a vertical valve cylinder adjacent said explosion cylinder, a piston valve in said valve cylinder for controlling communication to and from said explosion cylinder and driven by the engine, an oil tank in the lower end of said valve cylinder, a chamber above said valve and explosion cylinder, a screen in said chamber above said valve cylinder, means for directing oil from said tank against said screen, whereby a portion of the oil collects upon said screen and drips upon the head of said cylinder and the remainder of the oil passes through said screen and collects in said chamber for cooling said expansion and valve cylinders, and passages from said chamber and through said valve for returning surplus oil to said tank.

In testimony whereof I affix my signature.

MICHAEL J. MORAN.
